UNITED STATES PATENT OFFICE.

FREDERIC AUMONIER, OF LONDON, ENGLAND.

DESIGN FOR WALL-PAPER.

SPECIFICATION forming part of Design No. 22,958, dated December 5, 1893.

Application filed October 20, 1893. Serial No. 488,752. Term of patent 3½ years. Registered in England December 21, 1892, No. 204,618.

To all whom it may concern:

Be it known that I, FREDERIC AUMONIER, (trading as WM. WOOLLAMS & Co.,) a subject of the Queen of Great Britain, and a resident 5 of 110 High Street, near Manchester Square, London, England, have invented a new and original Design for Wall-Paper, (registered in Great Britain on the 21st of December, 1892, No. 204,618,) of which the following is a specification.

This design for wall paper as represented by the accompanying drawing consists of stems 10 of small leaves arranged somewhat of a pointed oval shape and from the center project stems carrying lily like flowers. The leaved stem 15 patterns are arranged to run at an angle from the horizontal and branches carrying ornamental scrolls and a flower run from the stems of the flowers in the leaf design to the stems of the flowers in the next design above at each side. 20

I claim—

The design for wall paper substantially as herein shown and described.

The 10th day of March, 1893.

FREDERIC AUMONIER.
